DESIGN FOR A MEDICINAL MEASURING CUP

George P. Kingsbury, Hollis, N. Y.

Application September 15, 1938, Serial No. 79,915

Term of patent 14 years

To all whom it may concern:

Be it known that I, George P. Kingsbury, a citizen of the United States, residing at Hollis, in the county of Queens and State of New York, have invented a new, original, and ornamental Design for a Medicinal Measuring Cup, of which the following is a specification, reference being had to the accompanying drawing, forming a part thereof, and in which

Figure 1 is a perspective view of the cup with the smaller spoon-shaped measuring cavity up-

permost and with the handle facing in one direction, and

Figure 2 is a perspective view of the cup with the larger spoon-shaped measuring cavity uppermost and with the handle facing in the opposite direction.

I claim:

The ornamental design for a medicinal measuring cup, substantially as shown.

GEORGE P. KINGSBURY.
